(57) **CLAIM**

I claim the ornamental design for the light bulb and socket, as shown and described in the drawings.

DESCRIPTION

FIG. 1 is a rear perspective view of a light bulb in accor-

dance with the new design with the broken line showing for illustrative purposes only and showing no part of the claimed design;

FIG. 2 is a front view of the light bulb in accordance with the embodiment of the new design shown in FIG. 1;

FIG. 3 is a top view of the light bulb in accordance with the embodiment of the new design shown in FIG. 1;

FIG. 4 is a side view of the light bulb in accordance with the embodiment of the new design shown in FIG. 1;

FIG. 5 is a rear view of the light bulb in accordance with the embodiment of the new design shown in FIG. 1;

FIG. 6 is a front perspective view of the socket in accordance with the new design;

FIG. 7 is a top view of the socket in accordance with the embodiment of the new design shown in FIG. 6;

FIG. 8 is a front view of the socket in accordance with the embodiment of the new design shown in FIG. 6;

FIG. 9 is a side view of the socket in accordance with the embodiment of the new design shown in FIG. 6;

FIG. 10 is a rear view of the socket in accordance with the embodiment of the new design shown in FIG. 6;

FIG. 11 is a rear perspective view of another embodiment of the light bulb shown in FIG. 1;

FIG. 12 is a front view of another embodiment of the light bulb shown in FIG. 1;

FIG. 13 is a top view of another embodiment of the light bulb shown in FIG. 1;

FIG. 14 is a side view of another embodiment of the light bulb shown in FIG. 1; and,

FIG. 15 is a rear view of another embodiment of the light bulb shown in FIG. 1.
